LOCK EMBODYING A KEY-EJECTING MECHANISM

Aniceto R. Visitacion, New York, N. Y.

Application February 16, 1949; Serial No. 76,740

3 Claims. (Cl. 70—383)

1

This invention relates to a key ejecting mechanism for ignition, household, and other locks of conventional make.

The principal object of this invention is the provision of a key ejecting mechanism which is adapted to eject a key from a cylinder lock when the cylinder of the lock is in locked condition. The mechanism is prevented from ejecting the key when the cylinder is in unlocked condition.

Key ejecting mechanisms have heretofore been devised and patented. In all cases, known to applicant, however, special locks were needed to accommodate the key ejecting mechanisms. The present invention, on the other hand, is of a key ejecting mechanism which is so designed as to adapt it for incorporation into conventional cylinder locks. The key ejecting mechanism of the present invention automatically ejects the key from a locked lock, but it is prevented from ejecting the key from a lock the cylinder of which is in unlocked condition.

It is accordingly a second object of the invention to provide a key ejecting mechanism of the character described, which is suitable for use in connection with conventional cylinder locks of various types.

The invention herein claimed will hereafter be described in terms of its application to a cylinder lock of the household type. It will be understood, however, that this type of lock is merely illustrative of the many types to which the present invention is applicable. The drawing also illustrates the application of the present invention to this type of lock but again this should be understood as being merely illustrative of the present invention.

The invention is not limited to those types of locks in which it is desirable that the key remain in the lock when the latter is in unlocked condition. It is desirable, in many cases, to withdraw the key from the lock when the key is in unlocked condition, as well as when it is in locked condition. In such locks, the key occupies the same position when the lock is in unlocked condition that it occupies when the lock is in locked condition. Hence, the key ejecting mechanism of the present invention is free to act upon the key in either case. In those locks where it is desirable that the key remain in the lock when the latter is in unlocked condition, the unlocked position of the key is different from its locked position. The key-ejecting mechanism is free to eject the key when the lock is in locked condition, but the key is so positioned when the lock is in unlocked position that the key-ejecting mechanism cannot eject it from the lock.

It is quite conceivable that under certain circumstances, it would be desirable to withdraw the key from the lock when the latter is in un-

2

locked position and to leave the key in the lock when the latter is in locked position. This would constitute a situation which is quite the reverse of the first situation above described. The key-ejecting mechanism of the present invention is equally adapted for use in this third type of lock.

In all cases the key may be ejected only when the lock cylinder is rotatably positioned in its housing to enable its tumblers to align with their respective sockets in the cylinder housing so that the tumblers free the key and lock the cylinder against rotation in its housing.

A preferred form of the present invention is shown in the accompanying drawings, in which:

Fig. 1 is a face view of a conventional cylinder lock, such as is used in private homes.

Fig. 2 is a back view of the latching assembly of said cylinder lock.

Fig. 3 is a back view of the cylinder housing and cylinder of said lock.

Fig. 4 is a plan view thereof showing the key-ejecting mechanism of the present invention incorporated therein.

Fig. 5 is a side view thereof.

Fig. 6 is a side view of said cylinder and a sectional view through the latching mechanism connected thereto.

Fig. 7 is a side view of the key for said lock.

Fig. 8 is a perspective view of part of the key-ejecting mechanism.

Fig. 9 is a diagrammatic view similar to that of Fig. 6 showing the key in the lock against the action of the key-ejecting mechanism.

Referring now to the drawing, it will be noted that a cylinder lock of conventional make is mounted on a door 80 (Fig. 6). This cylinder lock includes a conventional cylinder or plug 81 rotatably mounted in cylinder housing 102 and a latching mechanism 82. A key 83, insertable into cylinder 81 actuates said cylinder to lock and unlock the latching mechanism through the instrumentality of bar or tongue 85. This bar is attached to the cylinder in conventional manner and when the cylinder is caused to turn, said bar or tongue turns with it. The latching mechanism includes a slotted member 86, which is connected to the roll-back 87 by which the bolt or latch 88 may be thrown in either direction. Tongue 85 is positioned to enter and engage said slotted member 86, so that when the cylinder is turned, said tongue causes said member 86 and the roll-back 87 to turn in corresponding direction and to corresponding extent so that the bolt of the lock may be thrown accordingly.

The slotted member is rotatably mounted on a plate 89, which is affixed to housing 90 of the latching mechanism. Hollow knob 91 is also turnably mounted on said housing 90 in axial alignment with slotted member 86 and tongue 85. Knob 91 is the conventional means of ac-

tuating bolt 88 from the inside of the door and without the aid of a key.

The key-ejecting mechanism of the present form of the invention comprises three major parts: a bar 95, a sleeve 96 connected to said bar, and a compression spring 97 which is mounted in hollow knob 91 and which abuts the free end of sleeve 96. This sleeve is non-circular in cross section, and it is slidably mounted on tongue 85 of cylinder 81. Bar 95 is so positioned on said sleeve, that it is unable to reach through the keyhole or slot 98 (see Figs. 1 and 6), of the cylinder to block the introduction of the leading end of a key. The free end of sleeve 96 is so positioned as to provide for engagement with slotted member 86 (Fig. 2). Compression spring 97 is mounted on the free end of tongue 85 and it tends to resist inward movement of sleeve 96 into housing 90.

When key 83 is inserted into keyhole or slot 98 of cylinder 81, it engages bar 95 and pushes said bar outwardly from said keyhole and in the direction of the latching mechanism above described. At the same time the key moves the lock tumblers to free or unlock the cylinder or plug for rotation relative to its housing. Since bar 95 and sleeve 96 are connected to each other, this has the effect of pushing said sleeve inwardly through slotted member 86, into housing 90 against the action of compression spring 97. Should the key be released by the user without turning it in the cylinder, said spring would act upon sleeve 96 to push it back to its original position (shown in Fig. 6) and by the same token bar 95 would be pushed back to its original position in key slot 98, thereby ejecting the key from said key slot. When, on the other hand, the key is turned with said cylinder from its position shown in Fig. 9 to any other angular position in the lock, said key will be prevented from moving out of the key slot in response to the action of spring 97, by reason of the engagement with said key of the cylinder tumblers. The key will be ejectable from the cylinder only in the locked position of said cylinder relative to its housing, shown in Figs. 6 and 9.

A torsion spring 100 is affixed to the rear of cylinder housing 102 to return the cylinder to its locked position from any other position to which it may have been turned. This torsion spring is attached at one end to a fixed post 101 (Fig. 4) on the cylinder housing 102 and the opposite end of the spring is attached to a cylindrical member 103 through which tongue 85, sleeve 96 and bar 95 extend. Cylindrical member 103 moves integrally with the cylinder 81. Hence, when the cylinder is turned by key 83 to unlocked position, cylindrical member 103 will turn integrally therewith against the action of torsion spring 100. When the key is released in such position, the torsion spring tends to return the cylinder to its original locked position, thereby freeing the key for ejection by the key-ejecting mechanism above described. It will be understood, therefore, that the torsion spring serves the purpose of returning the cylinder to locked position when the operator thereof forgetfully or absentmindedly fails to return it to locked position himself.

It will be apparent from the foregoing that although only one form of the invention has herein been shown and described, other forms of the invention are equally feasible under the broad principles of the present invention, as well

as modifications of the form thus shown and described.

Having thus described my invention, what I claim as new and desire to secure by Letters Patent, is:

1. A cylinder lock comprising a cylinder having a keyway, a tongue connected to said cylinder, a latching mechanism, a key-ejecting bar slidably mounted in said keyway, a sleeve slidably mounted on said tongue, said sleeve being in slidable engagement with the latching mechanism and being also in operative engagement therewith, said sleeve and said bar being fixed against relative movement, a tension member disposed between said latching mechanism and one end of said sleeve to resist the inward movement of said sleeve and bar in response to the pushing engagement with said bar of a key being inserted into said keyway.
2. A lock of the character described comprising a cylinder lock having a keyway formed therein, a latching mechanism, a tongue connected to said cylinder lock and engaging said latching mechanism for actuating said mechanism when said cylinder lock is itself actuated by means of a key in its said keyway, and a key-ejecting mechanism slidably mounted on said tongue and in said keyway for ejecting the key therefrom when the key is releasable from the lock, said ejecting mechanism comprising a sleeve which is slidable on said tongue, said sleeve and said tongue being fixed against relative angular movement, said sleeve being engageable, together with said tongue, with the latching mechanism to actuate said latching mechanism when the lock is actuated by its said key, a key-ejecting bar connected to said sleeve and slidably mounted in said keyway, and spring means connected to said sleeve for tensionally maintaining said ejecting bar in said keyway, whereby said ejecting bar applies tensioned pressure against the key to force the key out of the keyway when the key is releasable from the lock.
3. The combination with a latch mechanism, a cylinder type of lock which has a keyway for a key, and a tongue which is adapted to actuate the latch mechanism, said tongue being attached to said cylinder; of a key-ejecting mechanism, said mechanism comprising a sleeve slidably mounted on said tongue, a key-ejecting bar fixedly connected to said sleeve and extending into said keyway in blocking position relative to a key being inserted therein, a compression spring mounted on said tongue and having one end bearing against a part of the latch mechanism and the other end bearing against said sleeve to yieldingly resist inward movement of the sleeve as well as of the bar when a key is inserted into the keyway in pushing engagement with said bar.
